COMBINATION UTILITY TOOL

William Andrew Uttz, Fort Worth, Tex.

Application November 27, 1953, Serial No. 27,824

Term of patent 14 years

(Cl. D54—13)

To all whom it may concern:

Be it known that I, William A. Uttz, a citizen of the United States of America, residing at Fort Worth, in the county of Tarrant and State of Texas, have invented a new, original, and ornamental Design for a Combination Utility Tool, of which the following is a specification reference being had to the accompanying drawing, forming part thereof.

Fig. 1 is a side elevational view of a combination utility tool, showing my new design, the opposite side being plain;

Fig. 2 is a top edge view thereof; and

Fig. 3 is a bottom edge view thereof.

I claim:

The ornamental design for a combination utility tool, substantially as shown and described.
